UNITED STATES PATENT OFFICE.

ARTHUR H. WESTON, OF NEW YORK, N. Y., ASSIGNOR TO THE T. H. SYMINGTON COMPANY, OF NEW YORK, N. Y., A CORPORATION OF DELAWARE.

CHEEK PLATE.

Application filed January 23, 1922. Serial No. 531,223.

To all whom it may concern:

Be it known that I, ARTHUR H. WESTON, a citizen of the United States, residing at New York, in the county of New York and 5 State of New York, have invented certain new and useful Improvements in Cheek Plates; and I do hereby declare the following to be a full, clear, and exact description of the invention, such as will enable others 10 skilled in the art to which it appertains to make and use the same.

My invention relates to the construction of cheek-plates of the type employed in the well known form of draft rigging mechanism 15 commonly designated as the Farlow two-key draft gear attachments. The primary object of the invention is to produce a cheek-plate of the type referred to which will efficiently fulfil the requirements 20 of operating conditions and be capable of application to the car underframe with a minimum expenditure of labor for fitting.

The principal feature of the invention, generally stated, consists in forming the 25 cheek-plate with a body web affording means for riveting or suitably securing it to the center sill or draft sill of a car and in providing it with a plurality of key-receiving slots which are adapted to register 30 with a continuous slot formed in the car sill to which the cheek-plate is applied; the cheek-plate also being furnished between its slots with a portion adapted to project through the slot in the car sill.

A further feature of the invention consists in providing a cheek-plate with a body 35 web affording means for securing it to the center sill or draft sill of a car having a continuous slot therein, and in providing a plurality of key-receiving slots adapted to register with said continuous slot, the structure 40 also being formed on one side of its web with flanges which respectively border its slots and project from said web to a greater extent at the adjacent ends of the 45 slots in the cheek-plate than at the remote ends of said slots.

As will hereinafter appear, there are other 50 features of the invention residing in particular details of construction.

In the drawings illustrating the invention, the scope whereof is pointed out in the claims:

Figure 1 is a horizontal sectional view 55 of a pair of cheek-plates embodying the in-

vention, showing their relation to the center sills of a car and to the form of draft gear attachments with which they are especially suited to be employed.

Figure 2 is an elevational view of a portion 60 of the inner side of one of the car sills, showing the cheek-plate attached thereto.

Figure 3 is a horizontal sectional view of the cheek-plate.

In the well known Farlow two-key draft 65 gear mechanism illustrated in the drawing, the car coupler 1 is operatively connected to the draft yoke 2 by a transverse key 3 which extends through a slot 4 in the shank of the coupler, through elongated slots 5 at 70 the forward ends of the arms of the yoke, through the center sills or draft sills 6 of the car underframe, and through suitable elongated slots 7 with which the cheek-plates applied to the said sills are provided toward 75 their forward ends. At the rear end of the coupler shank is a slotted follower block 8 receiving a key 9 which passes through elongated slots 10 in the arms of the draft 80 yoke 2, through the car sills 6, and through suitably elongated slots 11 with which the cheek-plates are furnished. As is understood by those skilled in the art, the car coupler 1 of this type of mechanism upon performing a buffing operation causes the 85 follower block 8 and the two keys 3 and 9, respectively, to travel rearwardly in the corresponding slots of the cheek-plate and of the draft yoke 2, the latter being prevented from retreating by means of a suitable back stop or by abutments (not shown) 90 rigidly secured to the car. When, however, the coupler 1 is pulled outwardly the key 3 draws the yoke 2 along with it, while the rear key 9 by bearing against the cheek- 95 plates at the forward ends of their slots 11 arrests the follower block 8 and transfers the pressure to which the latter is subjected to the cheek-plates and thence to the center sills or draft sills 6. While the cheek-plates 100 are especially well adapted for use in conjunction with the particular type of draft gear attachments which have been described, it is to be understood that these special details of construction are not disclosed with 105 the intent to limit the cheek-plates to use therewith.

Instead of forming the center sills or draft sills with separate slots for the respective keys 3 and 9 as has heretofore been cus- 110

tomary, each of the sills 6 is provided with a single continuous slot 12 which is of somewhat greater length than the distance separating the forward end of the cheek-plate slot 7 from the rear end of the cheek-plate slot 11.

Each cheek-plate 13 is formed with a body web 14 which is adapted to contact the outer side of the web of the adjacent sill 6 and is provided with suitable openings whereby it may be rigidly secured to the neighboring sill by suitable means, such, for example, as the rivets 15. The cheek-plate 13 is formed with two independent horizontally aligned slots, 7 and 11, respectively, the former being for the reception of the key 3 and the latter for the key 9. Projecting inwardly from the web 14 and bordering the slot 7 is a flange 16; and the slot 11 of the cheek-plate is similarly bordered by an inwardly projecting flange 17. These bordering flanges 16 and 17 are adapted to project through the continuous slot 12 formed in the neighboring car sill 6.

The parts of the flanges 16 and 17 which are at the adjacent ends of their respective slots 7 and 11 are integrally united and braced by a portion of the cheek-plate which also extends into the slot 12 of the car sill, the said uniting portion preferably comprising a plurality of spaced webs 18 integrally united to the body web 14 and respectively forming connecting prolongations of the portions of the flanges 16 and 17 bordering the upper and lower margins of the slots in the cheek-plate.

For a portion of its length the flange 16 preferably slopes, as at 19, toward the body web 14 from the neighborhood of the inner end of the slot 7 toward the outer end of said slot. Adjacent the inner end of the cheek-plate the flange 17 forms a key-bearing portion 20, to the rear of which and spaced therefrom is a sill engaging flange 21 preferably united to said key bearing portion by inclined tapering webs 22. This not only efficiently braces the portion of the cheek-plate which is between the slots 7 and 11 against such strains as may be communicated to the cheek-plate by the keys 3 and 9, but it effects an advantageous distribution of metal decreasing the weight of the device and reducing the difficulties of perfect casting and also effectually transmits to the sills the buffing shocks delivered thereto by the key 9. Moreover, the bordering flange 16 when thus formed affords

ample clearance for the draft yoke 2 and the inward projection of the flange prevents all wear upon the sill due to the movement of the yoke in service.

The slots 7 and 11 are preferably also bordered on the outer side of the cheek-plate 13 with flanges 23 and 24, respectively, the adjacent portions of which are preferably integrally united to each other and to the body web 14 by webs 25 corresponding to the webs 18 connecting the bordering flanges 16 and 17 on the opposite side of the body web.

By extending the key bearing portions of the cheek-plate inwardly of the sill faces I greatly increase the bearing area for the keys and reduce the unsupported portions of the keys to such extent that the keys are practically in direct shear under loads.

In applying the cheek-plates 13 to the car sill 6 it is only necessary to do the work required to permit the forward end of the inner bordering flange 16 and the rear end of the inner flange 21 to fit properly within the corresponding car sill slot and then to drive the rivets 15.

I claim:

1. A cheek-plate having a body web affording means for securing it to a center sill or draft sill of a car, and having a key receiving slot adapted to register with a slot in the web of said sill, and being provided on opposite sides of said web with flanges bordering said slot, one of said flanges being adapted to project through and beyond the web of said sill to form a guiding surface.

2. A cheek-plate comprising a body web affording means for securing it to the center sill or draft sill of a car, and provided with a key receiving slot, a flange defining the marginal edges of said slot, said flanges being adapted to register with and extend through a slot in the said sill, the sill slot being of greater extent than the slot in said cheek plate, and means projecting from the web of said cheek-plate between said flanges, and additional means also connected to the web of said cheek-plate and projecting therefrom and interposed between the rear of said sill slot and the marginal flange of said cheek-plate slot for reinforcing said cheek-plate.

In testimony whereof I affix my signature.

ARTHUR H. WESTON.
